(57) **CLAIM**

The ornamental design for an expandable drinking flask, as shown and described.

DESCRIPTION

FIG. 1 is a front, top and right perspective of an expandable drinking flask showing my new design;

FIG. 2 is a rear, bottom and right perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The drinking flask is shown with a symbolic break in its height. The appearance of any portion of the article within the broken lines forms no part of the claimed design. The broken line showing of a lid is for the purpose of illustrating portions of the flask and forms no part of the claimed design.
